CONVERSION OF HYDROCARBON GASES

Robert F. Marschner, Chicago, Ill., assignor to
Standard Oil Company, Chicago, Ill., a corpora-
tion of Indiana

Application January 6, 1938, Serial No. 183,790

11 Claims. (Cl. 198—10)

This invention relates to conversion of mixtures of butanes and butylenes into motor fuel and particularly their conversion into octanes suitable for motor fuel and having high anti-knock characteristics. In the manufacture of motor fuels from crude petroleum, natural gases and cracking still products, the gasoline fraction commonly contains dissolved therein lower boiling hydrocarbons which are normally gaseous and which tend to increase the vapor pressure of the gasoline to an undesirable extent. It is common practice, therefore, to separate the normally gaseous hydrocarbons from the gasoline, particularly the propane which should be completely removed in order to reduce the Reid vapor pressure of the gasoline as much as possible. It is common practice to allow a certain amount of the butanes and butylenes to remain in the gasoline but the amount of butanes and butylenes occurring in casinghead gasoline and cracking still products in particular is ordinarily too great to permit allowing all of them to remain in the gasoline without excessively increasing the Reid vapor pressure which results in gasoline losses by evaporation.

It is the purpose of this invention to more economically utilize the excess butanes and butylenes and particularly the butane-butylene mixtures obtained from cracking processes, either directly from the stabilization of the cracked gasoline or indirectly by absorption from the cracking still gases. The butanes and butylenes thus obtained comprise a mixture of isobutylene, isobutane, normal butane and the two isomeric normal butylenes designated 1 and 2. Hereinafter mixtures of these various hydrocarbons of four carbon atoms will be referred to as "C₄ hydrocarbons". The C₄ hydrocarbons obtained from cracking still products will usually contain about 10-15% of isobutylene, 20-30% of normal butylenes, the remainder being iso-butane and normal butane. The amount of normal butane will usually exceed considerably the amount of iso-butane. The C₄ hydrocarbon fraction obtained from crude oil distillation and from casinghead gasoline and natural gases is substantially devoid of butylenes and when used in my process will be handled somewhat differently for this reason.

In order to convert the C₄ hydrocarbons to octanes it is first necessary to effect a polymerization or condensation of two molecules of the C₄ hydrocarbons and various methods have been proposed for accomplishing this result. One method consists of subjecting the butane or butane-butylene mixture to pyrolysis at high tem-

perature with the result that the butane is extensively decomposed with concurrent interaction to produce higher boiling compounds and fixed gases. The yield of octane and octene obtained by this process is restricted by the amount of fixed gas production and furthermore considerable tar and heavy products are produced in addition to the octane. Another process consists in subjecting the C₄ hydrocarbons to catalytic polymerization with the conversion of the unsaturated constituents into octene and other polymerization products, for example, by passing over fuller's earth or phosphoric acid. The octene may be later hydrogenated to produce octane. The purpose of my invention is to effect certain improvements in the latter process, by which higher yields of octane may be obtained and particularly those octane isomers may be obtained which possess the higher, more desirable anti-knock characteristics. The invention may be readily understood by referring to the accompanying drawing which forms a part of this specification and which shows diagrammatically the various steps of the process.

Referring to the drawing, C₄ hydrocarbons are introduced by line 10 leading to heater 11 where the temperature is raised to about 250-350° F. The heated hydrocarbons are conducted by transfer line 12 under pressure of about 50 to 200 pounds per sq. in. to catalyst chamber 13 where the heated "butanes" are intimately contacted with a bed of catalytic material. On contact with the catalyst the butylenes, and especially the isobutylene in the hydrocarbon stream, are polymerized to produce iso-octenes and some of the butylenes also react with the butanes to produce octanes. The octenes and octanes produced in this manner are branched chain compounds and are ordinarily called iso-octenes and iso-octanes respectively. They are especially valuable for motor fuels because of their high antiknock characteristics. The normal octane, on the other hand, is quite undesirable as a motor fuel because of its pronounced tendency toward detonation. Higher pressures may be employed in the polymerizer 13, for example 1000 lbs., in which case the reacting mass will be largely in the liquid phase.

The catalyst employed in chamber 13 may suitably be phosphoric acid deposited on silica, for example infusorial earth may be mixed with phosphoric acid and formed into granules for the purpose. Other catalysts may be employed, such as H₂SO₄, ZnCl₂, fuller's earth, etc. With different catalysts, different temperatures and pres-

sures are usually desirable. After passing through the catalyst in chamber 13 the "butanes" are conducted by line 14 to heat exchanger 15 and condenser 16 wherein the polymerized products are condensed and separated as a liquid layer in separator 17. This liquid, consisting mostly of octenes, is withdrawn by line 18 and pump 19 which forces it into fractionator 20 where unchanged C₄ hydrocarbons are removed as a vapor by line 21. Octenes are withdrawn by line 22 and forced by pump 23 into heater 24 where the temperature is increased to about 500-700° F. Hydrogen introduced by line 25 is simultaneously heated with the octenes and the mixture is conducted by line 26 at a pressure of 500 to 3000 lbs. per sq. in. to the hydrogenation chamber 27, suitably charged with a hydrogenation catalyst which may be molybdenum sulfide, zinc chromate, etc. or, if desired, hydrogenation may be conducted at lower pressures, and temperatures by employing the metal type catalysts such as nickel, platinum, etc. Pressures used with the metallic catalysts of the nickel type or refractory oxide catalysts of the copper chromite type may be in the range of atmospheric to 200 lbs., in which case pump 23 may be dispensed with. Nickel or copper chromite may be employed at a temperature of about 500° F.

The octenes are converted by hydrogenation in 30 27 to octanes which are withdrawn by line 28 and condensed in condenser 29, from which they are discharged to receiver 30, from which excess hydrogen may be separated by line 31 and the final product withdrawn by line 32.

35 The uncondensed gases in separator 17, consisting principally of butanes with some n-butylenes, are withdrawn by line 33 leading to heat exchanger 15 where they are heated and thence by line 33a to furnace 34 where the temperature is further raised to about 850-1000° F. The pressure is reduced in line 33a by pressure reducing valve 36 to approximately atmospheric or slightly higher, e. g., 50 pounds per sq. in. The gases are introduced by line 35 into dehydrogenating 40 chamber 37 where they contact a suitable dehydrogenating catalyst, which may be the same catalysts as were employed in hydrogenator 27, with the exception of platinum, but due to the higher temperature and lower pressure in dehydrogenator 37 and the necessity for occasional regeneration, these catalysts may be prepared or pretreated in a different way. The temperature of dehydrogenation chamber 37 may be 850-1000° F. The mixture of gases is withdrawn 45 by line 38, cooled by heat exchanger and cooler 39 and then forced by compressor 40 into fractionator 41 where hydrogen is separated from the butylenes produced by the dehydrogenation. Cooling coil 42 serves to condense out hydrocarbons from the hydrogen gas which is then conducted by line 43 to compressor 44 and by line 25 to heater 24 previously described. The pressure to which the hydrogen is compressed by compressor 44 will depend upon the pressure required for the hydrogenation operation in chamber 27. Where nickel or other metallic catalyst or copper chromite is employed therein it is not necessary to employ high pressures and, in fact, the hydrogenation may be conducted at approximately atmospheric pressure, although it is usually desirable to employ somewhat higher pressures, e. g., 100-500 lbs. per sq. inch. Where sulfide active catalysts of the type of molybdenum sulfide and certain chromates are employed, much higher pressures are necessary, e. g., about 2,000

5 pounds per sq. inch. In this case it will be necessary to operate compressor 44 whereas in the case where nickel catalysts are used compressor 44 may be bypassed. It may be necessary when employing nickel catalysts, to regulate the sulfur content of the polymer, preferably by introducing a scrubber in line 10.

10 Returning to fractionator 41, any high boiling constituents of the stream withdrawn from dehydrogenator 37 may be discarded by line 45. 10 "Butanes" containing about 30-50% of butylenes are withdrawn as a side stream by line 46 and pump 47 and thence by line 48 to heater 11 previously described where the butylenes are combined with the mixed C₄ hydrocarbons, heated in 15 heater 11 and polymerized in chamber 13, increasing the yield of the desired butylene polymers obtained in this operation. In order to produce a polymer of higher antiknock value, however, I prefer to isomerize the butylenes to convert some of the 1-butene to 2-butene and isobutylene before polymerization. The butylenes in the stream flowing through line 48, contain a deficiency of isobutylene. I prefer to increase the concentration of normal 2-butene and isobutylene before introducing it into heater 11 and polymerizer 13 and this I may accomplish in the following manner. Valve 49 may be closed. Valves 50 and 51 may be opened to divert the stream of butylenes through heater 52 and catalyst chamber 53. Chamber 53 may be packed with a porous catalyst consisting of aluminum oxide, phosphoric acid disposed on silica (infusorial earth) or on silicates or on charcoal, and similar acid acting catalysts. If the temperature of the catalyst is maintained at about 400-480° F. the 1-butene is converted substantially to 2-butene and isobutylene which I have found to produce a motor fuel of higher antiknock value on subsequent polymerization. The 20 hot vapors from chamber 53 may be conducted by line 54 and valve 51 back to line 48 or heater 11 may be bypassed and the hot vapors from 25 53 may be conducted directly by line 55 to polymerizer 13 where the 2-butene and isobutylene are converted to octene of high knock rating.

30 By operating catalyst chamber 53 at a higher temperature, for example 480-620° F., preferably about 575° F., and employing a contact time of about 2 to 10 minutes, for example 5 minutes, 35 I may obtain a larger conversion of normal butylene into isobutylene, the amount of conversion depending on the contact time, temperature and the catalyst employed. Thus I may convert about 10 to 40% of the butylene to iso-butylene, 40 the remainder being largely converted from 1-butene to 2-butene. In one run over H₃PO₄-kieselguhr catalyst at 570° F. and 250 sec. contact time, 1-butene gave a gaseous product in which 50% of the olefin content was isobutylene. 45

50 Some polymerization of butylenes to octenes and even higher boiling compounds occurs simultaneously with the isomerization to isobutylene and I therefore prefer to introduce the product from this reaction by lines 54 and 55 directly 55 to the polymerizer and recover the polymers produced in chamber 53 along with the polymers obtained in chamber 13.

55 In order to reduce the extent of undesirable polymerization occurring in chamber 53 I may dilute the C₄ hydrocarbons entering chamber 53 by adding inert gases thereto, such as steam, nitrogen, hydrogen, etc. For this purpose hydrogen may be withdrawn from line 25 by line 56, or I may omit fractionator 41 and conduct 75

the dehydrogenated "butanes" and hydrogen directly from compressor 40 to isomerizer 53. When operating under these conditions, hydrogen will accumulate in the gases at the top of fractionator 20 and may be removed therefrom by condensing or absorbing the hydrocarbons recycled through line 21, in suitable apparatus not shown. Hydrogen separated in this way may be employed in heater 24 and hydrogenator 27, if desired.

In the operation of my process I prefer to polymerize in chamber 13 a hydrocarbon mixture containing at least as much isobutylene as 2-butene, as I have found that the motor fuel obtained from the polymerization of an equi-molecular mixture of these hydrocarbons has nearly as high a knock rating as the motor fuel prepared by polymerization of pure isobutylene. By polymerizing the mixture, therefore, I find it possible to produce motor fuel of extremely high octane number without the expense of converting all the raw material into isobutylene and purifying it. The exact composition of the copolymers is not known, but they are apparently highly branched octenes and de-decenes. I have found that whereas by polymerizing isobutylene alone with phosphoric acid and silica I may obtain a fuel having an octane number of about 100, if an equi-molecular mixture of isobutylene and normal 2-butene is employed I obtain a fuel (on reduction of the olefin to octanes) having an octane number of about 92-96. Polymerization of 1-butene, on the other hand, produces, under substantially the same conditions, after hydrogenation, a fuel having an octane number of less than 60 and the polymerization of 2-butene alone yields a fuel with an octane number of only about 70-80. It will be observed, therefore, that polymerizing a mixture of butylenes is distinctly advantageous and it is desirable to employ enough isobutylene in the mixture to equal or exceed the amount of normal butylenes present in order to obtain most satisfactory results. For this purpose I may introduce additional amounts of isobutylene by line 51. This isobutylene may be obtained by careful fractionation from butylene mixtures or by dehydration of isobutyl alcohol with alumina or thoria catalysts at about 750° F. It may also be obtained by introducing isobutane into dehydrogenation chamber 37 by line 37a. Normal butane may also be introduced by line 37a and later the resulting normal butene may be isomerized in chamber 53. C₄ hydrocarbons from natural gas, etc. which are substantially saturated may likewise be introduced at 37a. Thus I may employ somewhat lower or higher temperatures in polymerizer 13, for example 200 to 400° F. and in the isomerization step in 53 I may conduct the operation at temperatures as high as 800° F. The temperatures given are preferred with the catalysts described. Too low temperatures must be avoided in the isomerizer 53 to prevent excessive polymerization of olefins therein, but this difficulty may be largely overcome by reducing the time of contact and by diluting the gases with hydrogen, steam, etc.

Although I have described my invention with respect to certain embodiments thereof, it should be understood that it is not intended to limit it thereby, except insofar as set forth in the following claims.

I claim:

1. In the process of converting the unsaturated C₄ fraction of a commercial hydrocarbon gas mixture into motor fuel octanes of high knock

rating wherein said C₄ fraction contains a substantial amount of isobutylene together with normal butenes 1- and 2-, the improvement comprising subjecting said C₄ fraction to polymerization in the presence of an acid acting polymerizing catalyst at a temperature of about 250 to 350° F., whereby isobutylene is substantially copolymerized with said 2-butene into octene, separating the octene from the unconverted C₄ hydrocarbons and subjecting said octene to hydrogenation to produce octanes, subjecting the unconverted C₄ hydrocarbons to dehydrogenation in the presence of a dehydrogenating catalyst at a temperature of about 850 to 1000° F., whereby butanes are substantially converted to butenes, including 2-butene, and recycling said butenes thus obtained to said polymerization step with said C₄ fraction first mentioned thereby increasing the amount of 2-butene available and diminishing the amount of isobutylene polymer formation.

2. The process of claim 1 wherein said C₄ hydrocarbon fraction contains about 10 to 15% of isobutylene and about 20 to 30% of normal butenes.

3. The process of claim 1 wherein the butenes obtained from the dehydrogenation step are subjected to the action of an isomerizing catalyst at a temperature of about 400 to 480° F. and normal 1-butene resulting from said dehydrogenation is substantially converted to 2-butene before recycling to said catalytic polymerization step, thereby further increasing the amount of 2-butene available for co-polymerization with said isobutylene.

4. In the process of claim 1 wherein said C₄ hydrocarbon fraction contains insufficient isobutylene to co-polymerize all 2-butene present therein, the further improvement comprising subjecting butenes obtained from said dehydrogenation step to the action of an isomerizing catalyst at a temperature of about 480 to 800° F., whereby a substantial proportion of the normal butylenes contained in the dehydrogenation product are converted to isobutylene before recycling to said catalytic polymerization step.

5. In the conversion of an unsaturated C₄ fraction of hydrocarbons into high knock rating motor fuels within the gasoline boiling range, the improvement comprising adjusting the olefin composition of said hydrocarbon fraction to obtain an approximate isobutylene concentration at least equal to the concentration of normal 2-butene in said C₄ hydrocarbon fraction by subjecting said unsaturated C₄ hydrocarbons to the isomerizing action of an acid acting isomerization catalyst at elevated temperature whereby isobutylene is produced from normal butylenes contained therein, and subsequently subjecting said olefin mixture to polymerization in the presence of an acid acting polymerization catalyst whereby isobutylene and 2-butene are copolymerized to produce motor fuel octenes of high knock rating and separating said octenes from unpolymerized C₄ hydrocarbons.

6. The process of claim 5 wherein said acid acting catalyst is phosphoric acid disposed on a suitable solid supporting material.

7. The process of claim 5 wherein the said motor fuel octenes are converted into octanes by subsequent hydrogenation.

8. The process of claim 5 wherein the concentration of isobutylene in said unsaturated C₄ hydrocarbon fraction is adjusted by converting normal butylenes contained therein into isobutylene

by the action of phosphoric acid at a temperature of 480-800° F.

9. The process of converting a commercial C₄ hydrocarbon fraction into high knock rating motor fuels boiling within the gasoline range, which comprises dehydrogenating said C₄ fraction by the action of a solid dehydrogenating catalyst thereby converting a substantial proportion of said C₄ hydrocarbons into butylenes, subjecting 10 said butylenes to the action of an isomerizing catalyst whereby normal butylenes are substantially converted into isobutylene, subjecting said isomerized hydrocarbon mixture to the action of a polymerizing catalyst at a temperature above 15 250° F. whereby said isobutylene is co-polymerized with 2-butene to produce high knock rating

motor fuel, separating said high knock-rating motor fuel from unpolymerized hydrocarbon gases and recycling said gases to said catalytic dehydrogenation step first mentioned.

10. The process of claim 9 wherein the high 5 knock rating motor fuel obtained from said co-polymerization step is subsequently treated with hydrogen obtained from said dehydrogenation step in the presence of a suitable hydrogenating catalyst whereby said motor fuel is rendered substantially saturated.

11. The process of claim 9 wherein unconverted C₄ hydrocarbons from said co-polymerizing step are recycled to said dehydrogenating step.

15 ROBERT F. MARSCHNER.
